United States Patent Office

Des. 211,136
Patented May 21, 1968

211,136

SPORT VEHICLE

Ferdinand Alexander Porsche, Doffingen,
Boblingen, Germany

Filed Nov. 17, 1966, Ser. No. 4,712

Term of patent 14 years

(Cl. D71—1)

FIG. 3

FIG. 1

FIG. 2

FIG. 6

I claim:

The ornamental design for a sport vehicle, as shown and described.

UNITED STATES PATENT OFFICE
CERTIFICATE OF CORRECTION

Design No. 211,136

May 21, 1968

Ferdinand Alexander Porsche

It is hereby certified that error appears in the above numbered patent requiring correction and that the said Letters Patent should read as corrected below.

In the grant, lines 1 to 3, "Ferdinand Alexander Porsche, of Doffingen, Boblingen, Germany," should read -- Ferdinand Alexander Porsche, of Doffingen, Boblingen, Germany, assignor to Firma Dr. Ing. h.c.F. Porsche K. G., of Stuttgart-Zuffenhausen, Germany, --; line 13, "Ferdinand Alexander Porsche, his heirs" should read -- Firma Dr. Ing. h.c.F. Porsche K. G., its successors --; in the heading to the drawing and printed specification, line 4, "Boblingen, Germany" should read -- Boblingen, Germany, assignor to Firma Dr. Ing. h.c.F. Porsche K. G. Stuttgart-Zuffenhausen, Germany --.

Signed and sealed this 7th day of October 1969.

(SEAL)
